No. 783,735.

PATENTED FEB. 28, 1905.

J. ROEDIGER.

RATCHET BRAKE FOR STREET CARS.

APPLICATION FILED JULY 15, 1904.

Attest, III

Mr. Smith
Blanche & Rose

Inventor;

J. Roediger.

By Wright, Jr. Atty.

UNITED STATES PATENT OFFICE.

JACOB ROEDIGER, OF ST. LOUIS, MISSOURI, ASSIGNOR TO ST. LOUIS CAR COMPANY, OF ST. LOUIS, MISSOURI, A CORPORATION.

RATCHET-BRAKE FOR STREET-CARS.

SPECIFICATION forming part of Letters Patent No. 783,735, dated February 28, 1905.

Application filed July 15, 1904. Serial No. 216,635.

To all whom it may concern:

Be it known that I, JACOB ROEDIGER, a citizen of the United States, residing in the city of St. Louis, in the State of Missouri, have 5 invented certain new and useful Improvements in Ratchet-Brakes for Street-Cars, of which the following is a full, clear, and exact description, reference being had to the accompanying drawings, forming part of this specification.

My invention relates to ratchet-brakes of the type ordinarily used and operated by hand upon street-cars; and it is particularly adapted for street-cars equipped with vestibules 15 where an ordinary brake-handle cannot be positioned close to said vestibule and rotated all the way around.

The object of my invention is to produce what is commonly known as a "quarter-turn" 20 brake-handle and which when moved a slight distance rearwardly beyond its normal swing will automatically release from the brake-staff and allow said brake-staff to rotate during the unwinding of the chain and the release of the 25 brake-shoes.

Figure I is a plan view of a portion of a street-car platform with my improved brake in position thereon, the vestibule-windows being shown in section. Fig. II is a perspective 30 view of the bracket in which the upper end of the brake-staff is journaled and on which is fitted my improved ratchet-brake handle. Fig. III is a vertical section taken approximately on line III III, Fig. II. Fig. IV is a 35 horizontal section taken on line IV IV, Fig. III. Fig. V is a perspective view of the upper end of the brake-staff as contemplated by my improved construction. Fig. VI is a perspective view of the spring-actuated dog or 40 pawl which I make use of in carrying out my invention.

1 indicates the car-platform, and 2 the vestibule. A plate 4 is rigidly fixed to the vestibule-rail, with which plate is integrally 45 formed a vertically - arranged bearing 5, through which passes the upper end of the brake-staff 6. Formed integral with and projecting upwardly from the right-hand side of this bearing 5 is a lug 7, having an inclined

face 8, and immediately to the rear of the apex 50 of this lug is a notch 9. The end of the brake-staff 6 that projects above the bearing 5 is reduced in diameter, as indicated at 10, and a short distance below the extreme upper end of said reduced portion is formed a flange 11, 55 thus forming an annular groove or cut-away portion 12 between said flange and the body of the brake-staff. Formed in the face of the brake-staff 6, just below the reduced portion 10, is a series of notches 13, the same being 60 slightly inclined and corresponding to the inclined face 8 of the lug 7, previously mentioned. The base or lower end of the crank-handle 14 of my improved brake is provided with a vertical bore 15, fitted to receive the 65 upper end of the brake-staff 6, and said base is also provided with an integral housing 16, that contains a chamber 16^a, that communicates with said bore 15 and in which operates a spring-actuated dog or pawl 17. The lower 70 edge 16^b of this housing extends over and rides upon the upper edge of the bore 5. The pawl 17 is in the form of a hardened-metal plate provided with a laterally-projecting lip 18, that is adapted to enter the notches 13, and 75 said plate is necessarily arranged at an angle within the chamber 16^a corresponding to the inclination of the notches 13. Screw-seated in the housing 16 is a hollow cap 19, that contains an expansion coil-spring 20, which bears 80 directly against the face of the plate 17 and tends to force the lip 18 into the notches 13.

In the manipulation of my improved ratchet-brake the handle 14 is manually engaged and moved backward and forward, as indicated by 85 dotted lines in Fig. I, and during the backward movement or the movement toward the right the point of the pawl 17 travels by the notches until said brake-handle is brought to a stop. With the movement of said brake- 90 handle to the left the point of the pawl engages in one of the notches 13, and the brake-staff 6 will be thus rotated with the movement of the handle, and the brake-chain will be correspondingly wound upon the lower end of 95 said brake-staff. While the brake-handle is being moved to the right the brake-staff 6 is held against rotation by the usual ratchet and

pawl located upon the brake-staff just above the platform. When it is desired to allow the brake-staff to rotate in such a manner as to unwind the chain and release the brakes, the 5 operator moves the brake-handle 14 to the right until the housing 16 rides up the inclined face 8 of the lug 7. This movement necessarily carries the point of the pawl 17 upwardly out of the notch in which it has been 10 seated and into the annular space 12, and as soon as the brake-staff is thus freed it will rotate as the chain on the lower end of said brake-staff unwinds and the brake releases. The portion 16^b of the housing 16 after passing 15 over the apex of the lug 7 drops into the notch 9, and the brake-handle 14 thus remains elevated and in a position approximately parallel with the vestibule until the brake is released and until it is desired to again set the 20 brakes. When the operator desires to again manipulate the brake, the handle 14 is manually engaged and pulled toward the left, and in so doing the lower edge of the housing rides over the apex of the lug 7, and said brake- 25 handle is then free to descend into its operative position, during which action the point of the pawl 17 descends into one of the notches 13, this being easily accomplished owing to the corresponding inclination of the notches 13 30 with the inclined face 8.

It will thus be seen that I have constructed a ratchet-brake that is very simple, easily applied to brake-staffs, is very simple in manipulation, and is especially applicable for vestibule-cars and automatically releases the brake-staff when moved to the proper position.

I claim as my invention—

1. In a ratchet-brake, a brake-staff having a series of ratchet-teeth formed in its upper 40 end, a ratchet-handle mounted thereon, and means whereby said handle is moved upwardly away from the ratchet-teeth of the staff, substantially as set forth.

2. In a ratchet-brake, a brake-staff provided 45 at its upper end with a series of ratchet-teeth,

a handle rotatably arranged on the upper end of the staff, a pawl carried by the handle for engaging the ratchet-teeth, and means whereby the handle and pawl are elevated from the ratchet-teeth, substantially as set forth. 50

3. In a ratchet-brake, a brake-staff provided at its upper end with a series of ratchet-teeth, a fixed bearing for the upper end of the staff, a handle mounted upon the brake-staff above the fixed bearing, a pawl carried by said handle for engaging the ratchet-teeth, and means carried by the fixed bearing for elevating the handle at a certain period of its swing, substantially as set forth. 55

4. In a ratchet-brake, a brake-staff having a series of ratchet-teeth formed in its upper end, a handle mounted upon the upper end of said staff, a spring-actuated pawl carried by said handle for engaging the ratchet-teeth, whereby said handle is elevated to disengage the pawl from the ratchet-teeth, and means whereby said handle is held in an elevated position, substantially as set forth. 60

5. In a ratchet-brake, a brake-staff having a series of inclined ratchet-teeth formed in its upper end, a handle arranged for rotation on the upper end of the staff, a pawl in said handle held in an inclined position corresponding to the inclined position of the ratchet-teeth, and means whereby said handle and pawl are elevated to disengage the pawl from the ratchet-teeth, substantially as set forth. 70

6. In a ratchet-brake, a brake-staff provided with a series of ratchet-teeth in its upper end, a handle rotatively mounted on the upper end 80 of said staff, a pawl carried by the handle for engaging the ratchet-teeth, means whereby the handle is elevated to disengage the pawl from the teeth, and a stop formed on the staff for limiting the upward movement of the 85 handle and pawl, substantially as set forth.

JACOB ROEDIGER.
